INSULATED JUG

Joseph Tolciss, Bayside, N.Y., assignor to the United States of America as represented by the Secretary of the Army

Filed Jan. 15, 1964, Ser. No. 78,204

Term of patent 14 years

(Cl. D58—5)

FIG. 2

FIGURE 1 is a side elevational view of an insulated jug, embodying my new design, a part of the handle being broken away for purpose of illustration;

I claim:

The ornamental design for an insulated jug, substantially as shown.
